J. V. WESCOTT

TRACK GUARD RAIL

Filed July 29, 1926

Inventor
Jay V. Wescott
By Robert J. Michalek
Atty.

UNITED STATES PATENT OFFICE.

JAY V. WESCOTT, OF CHICAGO, ILLINOIS, ASSIGNOR TO DU-WEL STEEL PRODUCTS CO., OF CHICAGO, ILLINOIS, A CORPORATION OF ILLINOIS.

TRACK GUARD RAIL.

Application filed July 29, 1926. Serial No. 125,653.

The main object of the invention resides in the provision of a track guard rail which is light and strong, easily installed, and which is well adapted for its purpose, due 5 provision being made for securing the guard rail.

With this object in view my invention consists in certain features of novelty in the construction, combination, and arrangement 10 of parts by which the said object and certain other objects, hereinafter appearing, are effected all as fully described with reference to the accompanying drawing and more particularly pointed out in the claims.

15 In the said drawing—

Figure 1 is a top plan view of the track guard rail of my invention in its applied position with respect to a section of a traffic rail.

20 Figure 2 is a partial side elevation of the guard rail.

Figure 3 is an enlarged end elevation of the same.

25 Figure 4 is an enlarged partial side elevation of the guard rail showing the side of the same opposite that which is shown in Fig. 2.

Figure 5 is a section taken on the line 5—5 of Fig. 4.

30 Figure 6 is a section taken on the line 6—6 of Fig. 4.

Figure 7 is a partial section taken on the line 7—7 of Fig. 5.

35 Figure 8 is an enlarged partial top plan view of the guard rail with a portion broken away.

Like characters of reference indicate like parts in the several views.

Referring to the drawing the main or 40 body portion of the guard rail is of angle, preferably acute, cross section, one leg 1 of which angle section forms a base, and the other leg 2 of which angle section extends upwardly from the base and inclines toward 45 a traffic rail 3 of a track structure to which the guard rail is applied and has a wheel flange bearing surface 4 along its upper edge facing the head 5 of the traffic rail 3. The base 1 is provided at the ends thereof and 50 at intervals therebetween with downwardly offset portions 6 adapted to overlie and engage respective ties 7 of the track structure, and these portions 6 are extended laterally in both directions as indicated at 8 and 9, 55 the portions 8 underlying the traffic rail and

extending beyond the outer edge of the base 10 thereof. These extensions 8 and 9 are provided with spike apertures 11 whereby the extensions are spiked to the ties and with the traffic rail and ties, spike apertures of 60 the extensions 8, underlying the traffic rail, being disposed adjacent the outer ends of these extensions so that the traffic rail is spiked on the side thereof opposite that on which the body portion of the guard rail lies 65 and the spike apertures thereof including usual stepped spike apertures for the accommodation of traffic rails having base webs of different widths. See Fig. 1.

Transverse ribs 12 are disposed at the 70 intermediate of said downwardly offset portions 6 on both sides of said upwardly extending leg 2 of the body of the guard rail and bridge both angles between this leg and these downwardly offset portions. Additional transverse ribs 13 are disposed intermediate portions 14 of the base 1, intervening between the portions 6 of the base, and bridge the angle of these intervening portions 14 and the upwardly extending leg 2 75 80 and extend therefrom toward said traffic rail to engage under the head 5 thereof for the usual purpose.

The upper portions of the leg 2 adjacent the ends thereof gradually turn away from 85 the traffic rail 3 and slant downwardly toward said ends, as designated at 15, and form relatively low vertical end portions as designated at 16.

Laterally projecting formations, consisting of horizontal inner portions 17 connected with the leg 2 of the body portion of the guard rail and with adjacent ribs 13 and outwardly and downwardly inclined end portions 18 connected with the leg 2, the inner 90 95 portions 17 and the end downwardly offset portions 6 of the base, are formed at the ends of the body of the guard rail and project toward the traffic rail and form depth guards and are adapted to engage under the head 5 of the traffic rail for the usual purpose.

The downwardly offset portions 6 are gradually increased in width from the upwardly extending leg 2 to the outer edges of 105 said intervening portions 14, as designated at 19, and then the width of these portions 6 gradually decreases outwardly of the outer edges of said intervening portions, as designated at 20, to a normal width, whereby 110

the extending parts 8 of these portions 6 have a relatively great width at and about the inner edge of the base 10 of the traffic rail thus offering a relatively great resistance to bending or cracking at this point. The intervening portions 14 of the base 1 are preferably disposed at an acute angle with respect to the downwardly offset portions 6 of the base 1, and the ends of these intervening portions are curved downwardly, as designated at 21, and merge with the outer edges of the widened parts 19 of the portions 6, thus effectively tying the portions 14 and 6 together to form a continuous base and providing for the widening of the portions 6 in the plane thereof so that the base 10 of the traffic rail is not interfered with, the intervening portions 14, being disposed above the tie and roadbed level, providing against clogging in addition to reducing the weight of the guard rail without undue sacrifice of strength.

It will be observed that a light and strong structure is provided which is well adapted to withstand the strains and stresses incidental to use.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. In a track guard rail, in combination, a body portion of angle cross section, one leg of said angle section forming a base and the other leg extending upwardly from the base, said base having longitudinally spaced portions downwardly offset from the intervening portions of the base for engagement with respective ties of a track structure and extended laterally to underlie a traffic rail of the track structure, said downwardly offset portions being widened at the outer edges of said intervening portions and outwardly beyond the same and said intervening portions merging with said widened portions.
2. In a track guard rail, in combination, a body portion of angle cross section, one leg of said angle section forming a base and the other leg extending upwardly from the base, said base having longitudinally spaced portions downwardly offset from the intervening portions of the base for engagement with respective ties of a track structure and extended laterally to underlie a traffic rail of the track structure, said downwardly offset portions increasing in width from said other leg to the outer edges of said intervening portions and then decreasing in width to a normal width outwardly of the outer edge of said intervening portions said intervening portions merging with the outer

edges of said first mentioned parts of the widened portions of said downwardly offset portions.

3. In a track guard rail, in combination, a body portion of angle cross section, one leg of said angle section forming a base and the other leg extending upwardly from the base, said base having longitudinally spaced portions downwardly offset from the intervening portions of the base for engagement with respective ties of a track structure and extended laterally to underlie a traffic rail of the track structure, said downwardly offset portions increasing in width from said other leg to the outer edges of said intervening portions and then decreasing in width to a normal width outwardly of the outer edges of said intervening portions, said intervening portions turning downwardly at their ends and merging with the outer edges of said first mentioned parts of the widened portions of said downwardly offset portions.

4. In a track guard rail, in combination, a body portion of angle cross section, one leg of said angle section forming a base and the other leg extending upwardly from the base and inclining toward a traffic rail of a track structure to which the guard rail is applied, said base having longitudinally spaced portions downwardly offset from the intervening portions of the base for engagement with respective ties of the track structure and extended laterally to underlie said traffic rail, said downwardly offset portions being widened at the outer edges of said intervening portions and outwardly beyond the same and said intervening portions being disposed at an acute angle to said downwardly offset portions and merging with said widened portions thereof.

5. In a track guard rail, in combination, a body portion of angle cross section, one leg of said angle section forming a base and the other leg extending upwardly from the base and inclining toward a traffic rail of a track structure to which the guard rail is applied, said base having longitudinally spaced portions downwardly offset from the intervening portions of the base for engagement with respective ties of the track structure and extended laterally to underlie said traffic rail, said downwardly offset portions gradually increasing in width from said other leg to the outer edges of said intervening portions and then gradually decreasing in width to a normal width outwardly of the outer edges of said intervening portions, said intervening portions being disposed at an acute angle to said downwardly offset portions and curving downwardly at their ends and merging with the outer edges of said first mentioned parts of the widened portions of said downwardly offset portions.

6. In a track guard rail the combination of a body portion of angle cross section, one

leg of said angle section forming a base and the other leg extending upwardly from the base and inclining toward a traffic rail of a track structure to which the guard rail 5 is applied, said base having longitudinally spaced portions downwardly offset from the intervening portions of the base for engagement with respective ties of the track structure and extended laterally to underlie said 10 traffic rail, said downwardly offset portions being widened at the outer edges of said intervening portions and outwardly beyond the same and said intervening portions merging with said widened portions, trans- 15 verse ribs bridging the angle of said upwardly extending leg and said downwardly offset portions of the base, and additional ribs bridging the angle of said upwardly extending leg and said intervening portions of the 20 base and extending therefrom toward said traffic rail to engage under the head thereof.

7. In a track guard rail the combination of a body portion of angle cross section, one leg of said angle section forming a base and the other leg extending upwardly from the base and inclining toward a traffic rail of a track structure to which the guard rail is applied and having the upper portions thereof adjacent its ends gradually turned away 25 from said traffic rail and forming vertical end portions, said base having longitudinally spaced portions, at its ends and at intermediate points thereon, downwardly offset from the intervening portions of the base for engagement with respective ties of the track structure and extended laterally from said base in both directions, said downwardly offset portions gradually increasing in width from said upwardly extending leg 30 to the outer edges of said intervening portions and then gradually decreasing in width to a normal width outwardly of the outer edges of said intervening portions, said intervening portions being disposed at an acute 35 angle to said downwardly offset portions and curving downward at their ends and merging with the outer edges of said first mentioned parts of the widened portions of said downwardly offset portions, transverse ribs 40 at the intermediate of said downwardly offset portions on both sides of said upwardly extending leg and bridging both angles between this leg and these downwardly offset portions, additional transverse ribs bridging the angle of said intervening 45 portions of the base and said upwardly extending leg and extending therefrom toward said traffic rail to engage under the head thereof, and depth 50 guard formations at the ends of said upwardly extending leg and connected with the end portions thereof and with said downwardly offset portions at the ends of the guard rail and extending from said upwardly extending leg to engage under the 55 head of said traffic rail.

thereof, and depth guard formations at the ends of said upwardly extending leg and connected with the end portions thereof and 55 with said downwardly offset portions at the ends of the guard rail.

8. In a track guard rail the combination of a body portion of angle cross section, one leg of said angle section forming a base and the other leg extending upwardly from the base and inclining toward a traffic rail of a track structure to which the guard rail is applied and having the upper portions thereof adjacent its ends gradually turned away 60 from said traffic rail and forming vertical end portions, said base having longitudinally spaced portions, at its ends and at intermediate points thereon, downwardly offset from the intervening portions of the 65 base for engagement with respective ties of the track structure and extended laterally from said base in both directions, said downwardly offset portions gradually increasing in width from said upwardly extending leg 70 to the outer edges of said intervening portions and then gradually decreasing in width to a normal width outwardly of the outer edges of said intervening portions, said intervening portions being disposed at an acute 75 angle to said downwardly offset portions and curving downward at their ends and merging with the outer edges of said first mentioned parts of the widened portions of said downwardly offset portions, transverse ribs 80 at the intermediate of said downwardly offset portions on both sides of said upwardly extending leg and bridging both angles between this leg and these downwardly offset portions, additional transverse ribs bridging 85 the angle of said intervening portions of the base and said upwardly extending leg and extending therefrom toward said traffic rail to engage under the head thereof, and depth 90 guard formations at the ends of said upwardly extending leg and connected with the end portions thereof and with said downwardly offset portions at the ends of the guard rail and extending from said upwardly extending leg to engage under the 95 head of said traffic rail.

In witness whereof I hereunto affix my signature this 24th day of July, 1926.

JAY V. WESCOTT.
